US0D1081980S

(12) **United States Design Patent** (10) **Patent No.:** **US D1,081,980 S**
(45) **Date of Patent:** **** Jul. 1, 2025**

(54) **ABSORBENT ARTICLE**

(71) Applicant: **The Procter & Gamble Company**,
Cincinnati, OH (US)

(72) Inventor: **Emma Lynn Sartini**, Covington, KY
(US)

(73) Assignee: **The Procter & Gamble Company**,
Cincinnati, OH (US)

(**) Term: **15 Years**

(21) Appl. No.: **29/967,962**

(22) Filed: **Oct. 14, 2024**
